(57) CLAIM

The ornamental design of a physical exercise mat, as shown and described.

DESCRIPTION

FIG. 1 is a perspective top view of my new physical exercise mat;

FIG. 2 is a top plan view of my new physical exercise mat of FIG. 1;

FIG. 3 is a bottom plan view of my new physical exercise mat of FIG. 1;

FIG. 4 is a side elevational view of my new physical exercise mat of FIG. 1;

FIG. 5 is an end view of my new physical exercise mat of FIG. 1 from the left side of FIG. 4;

FIG. 6 is a side elevational view of my physical exercise mat from the side opposite that of FIG. 4; and,

FIG. 7 is an end view of my physical exercise mat from the end opposite that of FIG. 5.

The broken line drawing depicts environment and is not part of the claimed design.
